BUILDING CONSTRUCTION

Frank Streich, Chicago, Ill., assignor to Simplex
Metal Housing Corporation, Chicago, Ill., a
corporation of Illinois

Application December 9, 1935, Serial No. 53,578

7 Claims. (Cl. 189—86)

My invention relates to building constructions for houses and the like in which the outside surface or sheathing of the wall is of sheet metal. Such buildings ordinarily consist of a framework of steel beams resting upon a suitable foundation and walls of sheet metal panels attached thereto. It is ordinary practice to prepare the elements of the framework and the panels as far as possible at the factory, cutting them to size and otherwise manipulating them so that as little work as possible remains to be done upon them after they reach the site upon which they are to be erected. Such buildings and this practice of pre-fabricating the elements thereof as far as possible at the factory has marked advantages over the more ordinary methods of building formerly, and now, commonly in use, particularly in respect to economy, rapidity of erection and permanence. However, great difficulty has been encountered in making and maintaining such buildings and the walls thereof weather-tight. This is in large measure due to the expansion and contraction of the metal of which the elements of the structure are composed, particularly of the panels, due to changes in temperature to which they are exposed. Ordinarily the panels are of considerable size and this is desirable from the standpoint of economy, and it has been found particularly desirable to make the panels of considerable length, and lay them in horizontal courses in the walls. The effect of temperature changes is particularly important in the case of these larger size panels. If the panels are rigidly secured to each other at their meeting edges and to the framework as is the common practice, something must give with the expansion and contraction of the metal and the panels are either more or less buckled, warped and distorted in whole or in part or the fastenings by which they are secured together and to the framework are loosened or disrupted or both. As a consequence, even though as originally constructed, the joints between the panels are reasonably close and tight, they soon become more or less open for the passage of wind and rain-water. Caulking or filling the joints between the panels with a somewhat elastic or compressive material has not solved the difficulty.

My invention has for its object the remedying of the foregoing objections and providing walls for such buildings which are and remain substantially weather-proof. With this in view, I provide a construction in which the joints between adjacent panels are so formed and overlapped as to effectively preclude the passage of

air or water and which are also formed to permit a slipping of the panels with respect to each other and to the structural support or framework so that the panels may freely expand and contract with changes in temperature without buckling and distortion and without substantial change in their position in the building wall.

In the drawings accompanying and forming a part of this specification I have illustrated the invention in a preferred embodiment thereof, the drawings showing so much of a lower portion of a building embodying the invention, together with certain details thereof, as is necessary to an understanding of the invention.

In the drawings, Figure 1 is an isometric view of a portion of a building embodying my invention, partly in vertical section and partially broken away to better show the structure;

Fig. 2 is a plan view partly in section on the plane of the line 2—2 of Fig. 1;

Fig. 3 is a vertical section on the plane of the line 3—3 of Fig. 2;

Fig. 4 is a view similar to Fig. 3 but of a slightly modified form; and

Fig. 5 is an isometric view illustrating an interior or lining wall to be employed in buildings embodying my invention.

Referring first to the form of the invention illustrated in Figs. 1, 2 and 3, the structural framework is shown as comprising sill members 6 of plate metal and upright I-beams 7. The sill members, of course, rest upon and may be anchored to a suitable foundation of concrete or the like. Each sill member is of heavy sheet metal and formed at its outer edge with an upwardly extending flange 8 for a purpose which will appear. The I-beams, as shown, are formed each of two lengths or sections of heavy sheet metal each comprising a central web 7' having flanges 9 at the edges thereof, the two sections being suitably secured together at their webs by welding or riveting and together forming the complete I-beam. The I-beams may be secured to the sill in any desired manner though I prefer for this purpose the construction best shown in Figs. 1 and 2. In this construction one of the sections of the I-beam is so cut that the web extends beyond the flanges thereof and is struck up at right angles to the body of the web to form a laterally projecting flange 10. When the I-beam is in place in the framework, the flange rests upon the sill and is overlapped by a clip 11 welded or otherwise secured to the sill, see Fig. 1. The clips 11 may be secured in place on the sill at the factory and after the sills are suitably an-

chored on the foundation the upright beams may be placed on end thereon and manipulated to slip the flanges 10 thereof beneath the respective clips 11 and if desired the flanges 10 may be secured to the respective clips by spot welding.

In the preferred construction, the horizontal I-beams are arranged between opposite vertical beams to which they are secured and rest upon the sills at their respective ends. The horizontal I-beams 12 may be formed in the same manner as the vertical I-beams described but the webs of both sections thereof are prolonged and bent outward at their respective ends to form lateral flanges 14, 14, see Fig. 2. The preferred means for securing the ends of the horizontal beams to the lower ends of the vertical beams is by providing the adjacent portion of the flanges 9 of the latter with extensions 15 which are folded back toward the flanges, as shown in Fig. 2, to form channels which receive the flanges 14, 14 on the horizontal beams. These extensions 15 are preferably bent about the flanges 14 of the horizontal beams after the latter are in place. In the drawings I have shown only the horizontal beams for the lowermost floor but it will be obvious that a similar construction can be employed for the horizontal beams of the upper floors in the case of buildings of more than one floor. Other framework constructions may be employed in connection with the particular wall construction to which my invention more particularly relates.

The vertical beams are provided at suitable intervals, depending upon the height of the wall panel sections, with attaching clips 17. These clips are formed by folding small sections of sheet metal as at 18 to provide a leaf 19 which is secured by spot welding or otherwise to the upright, and a leaf 20 which is free at its upper portion to engage the wall panels or elements now to be described.

In the preferred construction the panels are substantially identical. Each comprises a rectangular main body portion 21 of the desired shape and dimensions which forms an element of the outer surface of the wall, and upper, lower and end flanges 22, 23, 24, 25, which are bent up from the edges of the sheet from which the panel is formed to constitute with the body portion a shallow pan. The sheet from which the panel is formed is so cut that provision is made at one end for forming not only the flange 25 but also an interlocking leaf or flap 26 by folding the sheet outwardly and rearwardly upon itself as at 26 to form with the flange a narrow channel or recess 27. When two such units are assembled end to end, flange 24 of the one unit enters the channel or recess in the folded end flange of the adjacent unit and the units are thus interlocked, the joint being substantially weather-proof, as will be seen in Fig. 2. In the completed wall each horizontal course is made up of a series of units so interlocked.

In laying out and cutting the blanks from which the panel is formed, the portion thereof from which the lower flange 23 is formed is cut of such width as to provide material to form also the channeled interlocking member 28. The material beyond the flange 23 is bent upwardly toward the center of the panel at 29 and then folded downwardly as at 30 to form the channeled interlocking member 28 on the free edge of flange 23. The extension of the blank from which the upper flange 22 of the panel is cut is of sufficient

breadth to provide also for an upwardly extending interlocking lip or leaf 31, see Fig. 3.

The channeled interlocking member 28 on each of the panels which are to constitute the lowermost course in the wall is so formed as to provide a recess 32 which will closely fit the edge flange 8 of the sill. In forming the wall from these panels or wall elements, the panels of the lower course are assembled and interlocked with each other and are interlocked with the flange 10 8 of the sill by bringing their channeled interlocking members into registry with the flange on the sill and pressing them downwardly until they occupy the position shown in Fig. 3. A weather-tight joint is thus formed with the sill, 15 which supports the panels, and the lip or leaf 31 on the upper flange of each panel fits against the corresponding clip or clips 17 on the upright beams. In locating the other successive courses of panels, the channeled interlocking member on the bottom of each panel is slipped over one or more clips 17 on the upright beams and also the lip 31 on the upper flange of the panel immediately beneath thus locking it in place. It will be clear that the interlocking construction 25 just described, by virtue of the downwardly open channel of an upper panel receiving the lip of the upper flange of the panel beneath forms a substantially weather-tight joint so that both the vertical and the horizontal joints in the wall construction are effectively proof against penetration by air flow and particularly against the entrance of water. Moreover, the species of joint described permits a sufficient sliding or slipping movement of the panels relative to each other 35 and to the framework to take up or allow for expansion and contraction of the panels due to changes in temperature and thus obviate strains and stresses in the panels due to heating and cooling which, as above stated, would otherwise 40 tend to warp and buckle the panels and loosen and disrupt the rigid fastenings or securing means.

I prefer to make the flanges of the panels of substantial depth to form in each a boxing or 45 pan and to locate therein in the case of each panel a substantial body of insulating material. Preferably I employ rigid blocks 35 of fibrous cemented material such as is now available on the market, which blocks are so cut as to closely 50 fit the pans or hollows of the panels and thus not only provide insulation but considerably contribute to the rigidity of the panels and support them against the effects of blows or the like.

In some situations, however, insulation is not 55 desirable or necessary and therefore the depth of the flanges of the panels as illustrated in Figs. 1, 2 and 3 may be reduced or substantially eliminated. In Fig. 4, I have illustrated such a modified construction. In this form of the invention 60 the pan flanges are substantially omitted and the lip 31' and the interlocking member 29' are formed substantially at the respective upper and lower edges of the body 21 though slightly offset with respect thereto. The adjacent edges of 65 panels in the same courses or tiers may be interlocked in substantially the same manner as described in connection with the panels of Figs. 1, 2 and 3 except that the interlocking members extend only a short distance from the panel body. 70

If a double wall structure having intermediate air spaces is desired, it may readily be provided by constructing an inner wall as shown in Fig. 5. In this case the uprights are provided on their inner as well as their outer faces with the clips 75

17, suitably spaced apart vertically. The inner wall may be formed of slabs 40 of rigid material such as the fibrous insulating material previously mentioned. In this event the inner as 5 well as the outer edge of each of the sill plates is formed with an upturned flange 41. The slabs constituting the inner wall are formed with grooves or kerfs in their upper and lower edges and metal strips 42 S-shaped in cross-section as shown in Fig. 5 are provided for securing the bottom edges of the slabs of the lowermost course to the sill. The upturned outer edge or flange 43 of the securing strip 42 enters the kerfs in the bottom edges of the slabs of the lowermost course and the other edge of the metal strip is formed to embrace the upturned flange 41 on the sill. Metal strips 45 somewhat similar to the strips 42 but specifically different may be employed between the courses of slabs for holding them in alignment and securing them to the uprights. As seen in Fig. 5, the strips 45 at one edge are formed like strips 42 providing a channel 46 for engaging the clips 17 on the upright beams. The other edges of the strips 45 are bent upwardly at right angles to the main body thereof as at 47 and then folded back as at 48 to provide an upwardly extending flange or rib which enters the kerf or groove in the lower edges of the slabs of the upper course and a flange which enters the grooves in the upper edges of the slabs of the lower course. Preferably the metal strips 42, 45 extend the entire length of the wall, though this is not essential and they may be made in sections.

38 If desired the slabs may be staggered from course to course as shown in Fig. 5.

The outer surface of the panels of the outer walls may be of any desired size and configuration. They may be so formed that the joints between them are not readily discernible, particularly when the wall is painted or otherwise surfaced, or the panels may be made of suitable size and chamfered at their outer edges to imitate cut stone, brick or the like.

45 It will be seen that my invention provides a wall construction the elements of which may be substantially and completely fabricated at the factory and speedily assembled into the building without any considerable manipulation after they leave the factory, and by reason of the particular nature or form of the joints between the panels and the provision for expansion and contraction the wall is substantially weather-proof and remains so.

55 I claim:

1. In a building construction of the class described, a supporting frame, panel supporting clips thereon, a series of superposed horizontal courses of panels constituting a wall, each of said panels formed of a continuous sheet of metal and comprising a rectangular body, a lip offset inwardly and extending upwardly from the upper edge of said body in a plane parallel to the latter, a folded interlocking member extending upwardly from the lower edge of the body in the same plane as said lip and having a channel therein opening downwardly, the channels of the interlocking members on the panels of each course except the lowermost receiving the lips of the panels of the course beneath them and also the adjacent supporting clips on the frame, each panel also having an inwardly extending straight flange at one end, and a flange on its other end extending inwardly and folded outwardly upon itself to form a recess which receives and inter-

locks with the straight end flange on the adjacent panel, all said lip, clip, flange and interlocking members being slip-fitted together independently of separate fastening means.

2. In a building construction of the class described, a frame structure comprising sill members, upright beam members of I-shape in cross section each including a central web portion having flanges at the opposite edges thereof, said web portions at one end being extended and turned at right angles to the plane of the web so as to seat upon the respective sill, clip means on the respective sill and forming a recess adapted to slidably receive the respective extended end of said web portion for interlockingly engaging said sills and upright beams, horizontally disposed beam members shaped similarly to said upright beam members and also having their web portions extended at one end at right angles similarly to the web portions of said upright beams, and extensions on the flanges of the upright beams folded over and upon the web portion extensions of the horizontal beams to interlockingly secure the horizontal beams upon the upright beams.

3. In a building construction of the class described, a frame structure comprising sill members, upright beam members of I-shape in cross section each including a central web portion having flanges at the opposite edges thereof, said web portions at one end being extended and turned at right angles to the plane of the web so as to seat upon the respective sill, clip means on the respective sill and forming a recess adapted to slidably receive the respective extended end of said web portion for interlockingly engaging said sills and upright beams, horizontally disposed beam members shaped similarly to said upright beam members and also having their web portions extended at one end at right angles similarly to the web portions of said upright beams, extensions on the flanges of the upright beams folded over and upon the web portion extensions of the horizontal beams to interlockingly secure the horizontal beams upon the upright beams, and clip members formed upon the flanges of said upright beams, opposite the flanges thereof to which said horizontal beams are secured, which clip members are adapted for supporting wall-forming elements.

4. In a building construction of the class described, a supporting frame, panel supporting clips thereon, a series of superposed horizontal courses of panels constituting a wall, the panels of each course being arranged in end-to-end abutting relation and having longitudinally extending recesses in both the upper and lower edges thereof, and means for supporting said panels in their superposed course and end-to-end relationship, which means comprises one or more members having a downwardly opening channeled leg portion adapted to slidably fit over and receive said panel supporting clips, and also having a T-shaped portion extending away from said channeled portion in horizontal direction so that one part of the T-head of said T-shaped portion engages in the bottom slots of the panels of one course and the other portion of its T-head engages in the uppermost slots of the panels of the next lower course, whereby all said panels are supported in slidable relation with respect to each other and to said frame and are held in a predetermined wall plane.

5. In a building construction of the class described, a horizontal sill member having upward-

- ly extending flanges at the opposite longitudinal edges thereof, an upright member resting upon said sill intermediate said flanges, a panel member disposed adjacent to one side of said upright member and interlocked against transverse movement with one of said upwardly extending flanges, a metal strip arranged in superposed relation to the other of said upwardly extending flanges and interlocked against transverse movement relatively thereto, and a panel member disposed upon the opposite side of said upright member above said metal strip engaging and overlying at least a portion of said metal strip and interlocked against transverse movement relatively to said metal strip.
6. In a building construction of the class described, an upright member, a horizontal sill member supporting said upright member and having an upwardly extending flange along one longitudinal edge thereof, a metal strip arranged in superposed relation and interlocked against transverse movement relatively to said flange, a retaining clip secured to said upright member above said upturned flange, a second metal strip disposed substantially parallel to said sill and interlocked against transverse movement relative to said retaining clip, and a slab or panel member disposed between said strips and interlocked against transverse movement with each of said strips.

7. In a building construction of the class described, a supporting frame including a sheet metal sill having a substantially flat horizontal web and an integral flange extending upwardly in a substantially vertical plane from an edge of said web; a plurality of studs mounted upon said sill and spaced inwardly from said vertical flange; horizontally and vertically spaced panel supporting clips on said studs, each of said clips having a panel retaining flange; and a series of superposed horizontal courses of panels constituting a wall arranged in confronting relationship to said studs, each of said panels being formed of a continuous sheet of metal and including a body having an upwardly extending lip at its upper edge and an upwardly extending channelled interlocking member at its lower edge lying in a plane substantially common to said lip, the channel of said interlocking member opening downwardly, the channel of the interlocking members of the panels of each of the courses except the lowermost slidably receiving the lip of subjacent panels and also receiving the panel retaining flange of certain of said clips, the interlocking member of the panels of the lowermost course slidably receiving the vertical flange of said sill and having a portion thereof disposed between said studs and said vertical flange.

FRANK STREICH.
